(57) **CLAIM**

The ornamental design for an egg holder, as shown and described.

DESCRIPTION

FIG. 1 is a rear/left/top perspective view of an egg holder; FIG. 2 is a front elevational view thereof, for which a rear elevational view would be a mirror image thereof; FIG. 3 is a top plan view thereof; FIG. 4 is a bottom plan view thereof; FIG. 5 is a left side elevational view thereof; and, FIG. 6 is a right side elevational view thereof. The broken lines representing the handle and the front facing wall form no part of the present invention.
